CLINKER DISPOSAL MEANS

Edward J. Anderson, Lincoln, Nebr.

Application December 15, 1941, Serial No. 423,082

10 Claims. (Cl. 110—165)

The present invention is concerned with clinker disposal means and more particularly with a device adapted to be associated with a furnace to facilitate the removal of clinkers and ashes therefrom.

In recent years, great strides have been made in eliminating the dust and dirt previously associated with coal burning furnaces. A widespread adoption of stokers has been primarily responsible for this. With the installation of stokers, the average householder usually becomes extremely interested in eliminating as far as possible any dust and fumes such as are ordinarily associated with a hand fired, coal burning furnace. While a stoker eliminates the creation of dust and fumes incidental to firing, it does not take care of the problem of disposing of ashes and clinkers, particularly the latter. In removing these in the conventional manner, it is almost impossible for the householder to avoid spilling a certain amount of ashes on the floor and permitting fumes from the furnace to pass out into the basement.

An object of the present invention is to provide an improved means for facilitating the removal of clinkers. In general, I propose to provide means whereby the clinkers may be removed from the furnace and conducted through a chute into a receptacle disposed closely adjacent the furnace.

While arrangements have been previously proposed for accomplishing the general object outlined above, these devices usually either formed part of the furnace proper or were so positioned as to interfere with an inspection of the furnace and in the case of a hand fired furnace, to interfere with the firing thereof.

Thus, a more specific object of the present invention is to provide an arrangement having a portion normally in an inoperative position so as not to interfere in any way with the access to the firing opening of the furnace and which can be moved to an operative position in which the removal of clinkers from the furnace to a suitable receptacle is facilitated.

A further object of the present invention is to provide an arrangement such as set forth in the last object in which the interior of the furnace is clearly visible when the clinker disposing arrangement is in its operative position.

A still further object of the present invention is to provide such an arrangement wherein there is a chute directly connected with the clinker receptacle by a connection which may be adjusted to permit removal of the receptacle.

A still further object of the invention is to provide such an arrangement in which provision is made for the apparatus closely engaging the furnace when in operative position.

5 A further object of the invention is to provide such an arrangement in which provision is made for carrying off the fumes from the clinkers into the furnace after the clinkers have been removed.

10 A further object of the present invention is to provide an arrangement of the type discussed which may be employed in connection with a stoker fired furnace in which the stoker enters the furnace in the front thereof.

15 Other objects of the invention will be apparent from a consideration of the accompanying specification, claims, and drawings, of which:

Figure 1 is a perspective view of my improved clinker disposal means associated with a stoker fired furnace;

20 Figure 2 is a view similar to Figure 1 but showing the clinker disposal means in operative position;

Figure 3 is a perspective view of the lid assembly employed in the clinker disposal device;

25 Figure 4 is a side elevational view of the clinker disposal means;

Figure 5 is a front sectional view, the section being taken along the line 5—5 of Figure 4;

30 Figure 6 is a perspective view of a modified form of lid assembly particularly adapted for a hand fired furnace;

Figure 7 is a front elevational view of a modified form of the clinker disposal device;

35 Figure 8 is a front elevational view of the lid assembly for the clinker disposal means of Figure 7;

Figure 9 is a vertical sectional view of a further modification, the section being taken along the line 9—9 of Figure 10 in the direction of the arrows; and

40 Figure 10 is a transverse sectional view of the modification of Figure 9, the section being taken along the line 10—10 of Figure 9 in the direction of the arrows.

45 Referring specifically to the drawings, a furnace assembly is generally indicated by the reference numeral 10. This furnace assembly is of a conventional type comprising the furnace 11 and the furnace jacket 12. The furnace 11 is provided with the usual clean-out door 13 and the firing door 14. The firing door is hinged in the conventional manner to the furnace as at 15.

50 Projecting into the furnace at the side thereof is a casing 16 enclosing the coal and air tubes

of a stoker 17. It will be understood that this casing extends into the furnace proper through the jacket 12. The operation of this stoker in supplying coal and air to the furnace is entirely conventional and forms no part, in itself, of the present invention.

The reference numeral 19 is employed to designate a rectangular chute formed of sheet metal or the like. This chute is supported on the floor of the furnace room and may be secured, if desired, to the furnace by suitable fastening means such as brackets 20.

Slidably secured within the chute 19 is a lid assembly 21. This lid assembly comprises a cover member 22 having downwardly extending flanges 27 to which are secured side wall members 24. These side wall members may constitute legs for the lid assembly where desired. Extending between the two side members 24 is a deflector plate 25, the ends of which are turned inwardly and secured to the side walls 24. As best indicated in Figure 3, this deflector plate 25 is of limited width and is spaced from the lid 22 a sufficient distance to permit the insertion of a shovel, tongs, or any similar furnace tool. A glass pane 23 is preferably secured in the lid assembly 22, particularly in cases where the fire bed is of such depth that it would be otherwise difficult to see the fire bed when the lid assembly is in the operative position. This glass pane may be of plate glass or wire reinforced glass to minimize the danger of the glass being broken. A handle 26, secured to the cover 22, is employed for raising or lowering the lid assembly 21, as will be explained later. A catch 28 is secured to the rear part of the cover 22 and is adapted to be engaged over the curved portion 29 of the furnace adjacent the fire door 14.

While the operation of the clinker disposing means will be referred to in greater detail later, it is to be noted at the present time that the lid assembly 21 is slidably secured within the chute 19 and is normally in the position shown in Figure 1 in which it is out of the path of the fire door 14 and interferes in no way with the injection and the normal operation of the furnace. When, however, it is desired to remove clinkers and ashes, the lid assembly 21 is moved to the position shown in Figure 2.

The chute 19 is adapted to communicate with a clinker receptacle 30 disposed within a pit 31. Pit 31 is normally covered by a lid 32 provided with a handle 33. The lid 32 may, if desired, be hinged to the floor as at 34.

It will be noted that the receptacle 30 is approximately the same cross-sectional configuration as the chute 19 and of the same size or slightly larger than the chute. In order to insure that the receptacle 30 will be properly positioned with respect to the chute 19 and to decrease to a minimum the chance of dust and ashes escaping into the furnace room, a sleeve 42 is provided between the chute 19 and the receptacle 30. This sleeve 42 is slidably secured within the chute 19 and is actuated by mechanism best shown in Figures 4 and 5. It will be noted that a rod 43 extends transversely through the chute 19 adjacent the front wall and is journalled in the side walls. The right hand end of the rod (as viewed in Figures 2 and 5) has a handle 36 secured to it. By means of this handle 36, the rod 43 can be readily rotated. Secured to rod 43 are a plurality of lever arms 37. The outer ends of these lever arms 37 are connected by means of links 38 to a pair of slidable bars 39. The bars 39, at their

upper ends, slidably extend through guide blocks 41 and, at their lower ends, are secured to the sleeve 42. It will be obvious from a consideration of Figures 4 and 5 that rotation of the handle 36 in a counter-clockwise direction will raise the sleeve 42 while rotation of the handle in a clockwise direction will lower the sleeve 42.

Where desired, a connection may be made between the interior of the chute 19 and the combustion chamber. Thus, referring to Figures 4 and 5, such an opening is indicated by the reference numeral 44. This opening permits the gases escaping from the clinkers after the lid assembly 21 has been lowered into the position of Figure 1, to pass into the combustion chamber and so out through the stack pipe.

Operation of species of Figures 1 to 5

As previously indicated, the parts are shown in their normal positions in Figure 1. When it is desired to remove clinkers, the fire door 14 is first opened. The handle 26 is then grasped and the lid assembly 21 is moved upwardly. Because of a slight looseness of fit, it is possible when the lid assembly is raised to move it forwardly to engage the catch 28 over the curved portion 29 or any similar projecting portion of the furnace so as to retain the lid assembly in the position shown in Figures 2, 4 and 5. It will be seen that when the parts are in this position, there is an opening bounded by the sides 24, the deflector 25, and the lid 22 which is of substantially the same size as the fire opening normally closed by the door 14. In spite of the fact that the depth of the fire opening has, in effect, been increased, it is still possible by reason of the glass pane 23 to view the interior of the combustion chamber so as to facilitate the removal of clinkers. The operator now inserts tongs or a similar clinker removing device and extricates the clinkers, drawing them out through the fire door opening and dropping them into the chute 19. The clinkers pass downwardly through chute 19 and sleeve 42 into receptacle 30. Due to the draft within the furnace, any gases which pass upwardly from receptacle 30 enter the combustion chamber and are drawn up the flue. As soon as the clinkers have been removed, the operator lowers the lid assembly 21, effectively closing off the outlet of chute 19 and preventing any further escape of gases. Any gases which are admitted will be retained within the chute assembly 19 and the receptacle 30, or where the opening 44 is provided, will pass into the furnace proper.

It will be seen that the operation of removing the clinkers has been accomplished without any danger of spilling the clinkers or ashes on the floor of the basement.

Furthermore, the arrangement does not in any way impede normal access to the furnace. In fact, the clinker disposal means may be entirely separated from the furnace, having no physical connection therewith.

When it is desired to remove the clinkers, the lever 36 is rotated in a counter-clockwise direction to move the sleeve 42 upwardly. This permits the receptacle 30 to be withdrawn from the position shown to a position underneath the lid 32. As soon as the sleeve 42 has been raised in this manner, the lid 32 is raised and the receptacle 30 is withdrawn from the pit through the opening normally covered by lid 32.

Modification of Figure 6

In Figure 6, I have shown a slightly modified

form of the lid assembly. In the first place, the cover 122 corresponding to cover 22 is made of metal throughout and has no glass pane therein. A handle 126 is secured to the center of cover 122. The side walls 124 are considerably longer than the side walls 24 of the previously described species so that the cover 122 is spaced a much greater distance from the deflector plate 125 than is cover 22 from the deflector 25. Secured to the inside of side walls 124 at the same position with respect to baffle 125 as cover 122 of the preferred species, are slotted retaining strips 130. Secured within these retaining strips is a pane of plate glass 123. Because of the position of retaining strips 130, the glass pane 123 occupies the same position with respect to the deflector 125 as does the lid 122 with respect to baffle 25. Thus, when the lid assembly of Figure 6 is raised upwardly, it is raised to a position wherein the glass pane 123 comes above the fire door opening. The arrangement of Figure 6 can be used with a hand fired furnace where there might be danger of the glass pane becoming broken during firing operations by reason of lumps of coal dropping on it. In the arrangement of Figure 6, the glass pane 123 is protected by the overlying metal cover member 122.

The lid assembly of Figure 6 is provided with a further feature which may, if desired, be employed with a lid assembly such as that of Figure 3. It will be noted that secured within the side walls 124, there is an inverted U-shaped sleeve 128. Secured to this sleeve 128 are a pair of bars 129 which are slidably secured in guides 132. The U-shaped sleeve 128 is employed where a lid assembly, upon being moved upwardly, cannot be made to firmly engage the edges of the firing opening. It often happens that the front of the furnace is so shaped that when the lid assembly is positioned so that it can be drawn vertically upwardly, it will be spaced slightly from the walls of the firing opening when it is moved to an operative position. When the sleeve member 128 is employed, it is possible to push inwardly on the bars 129, moving the sleeve 128 into engagement with the walls of the firing opening. In many cases, however, it is unnecessary to employ this sleeve due to the draft of the furnace being sufficient to prevent the escape of any gases through the narrow opening between the walls of the lid assembly and the walls of the firing opening.

Species of Figure 7

In Figure 7 I have shown a further modification particularly designed for the case in which the stoker enters the furnace from the front. While in the better stoker installations, there is a tendency to introduce the stoker from the side so as to facilitate normal access to the interior of the furnace, stokers are occasionally introduced from the front either for purposes of economy or because of lack of space at any other point. In such cases, it is obvious that the chute 19 cannot extend vertically upwardly as in the species of Figures 1 to 5. In this case, it is desirable to employ the arrangement of Figure 7 in which the upper portion of the chute 219 is inclined. In the arrangement of Figure 7, the lid assembly is slightly modified because of the inclination of chute 219. As shown in Figures 7 and 8, the cover 222 has one side wall 232 rigidly secured to it at right angles thereto. The other leg 233 is hinged as at 234 so as to be adapted to fold inwardly to assume the position shown in Figure 7.

Preferably, as shown in Figure 8, a spring 235 is secured to the cover 222 and biases the side wall 233 outwardly into a position in which it is at right angles to the plane of cover 222. In use, the side wall 233 is folded as shown in its lower position in Figure 7. Upon the lid assembly being drawn upwardly, the leg 233 is pushed outwardly by spring 235 until it assumes the position shown in the uppermost portion of Figure 7 in dotted lines and in Figure 8 in full lines. When the lid assembly is so moved upwardly, it is obvious that it can be used in the same way as the species of Figures 1 to 5.

Species of Figures 9 and 10

Occasionally, it may be undesirable to provide a pit within the basement. In such a case, the function of the chute 19 and receptacle 30 are both performed by a single member. Such an arrangement is shown in Figures 9 and 10. The lid assembly is designated by the reference numeral 321 and is identical to the lid 21 of the preferred species. In other words, this comprises a cover member 322 to which is secured side wall members 324. Extending between the two side wall members 324 is a deflector plate 325, the ends of which are secured to the side walls. As in the preferred species, a glass pane is secured in the lid assembly. A handle 326 is secured to the cover 322.

Instead, however, of a separate chute 19 and a receptacle 30, these two members are combined in one unit 340. This unit consists of a receptacle of a rectangular cross section substantially the same in configuration as the cover member 322. The receptacle comprises side walls 341 and 342, a front wall 344, and a rear wall 345. Secured within the receptacle 340 is an inner wall assembly 355 having a front inner wall 356 and side inner walls 357 and 358. As best indicated in Figure 9, these walls extend only a slight distance below the bottom of the side wall members 324 when the lid assembly is in its lowermost position. The inner wall assembly is retained in place by having the walls 357 and 358 secured to the rear wall 345 of receptacle 340 by brackets 359 or other suitable fastening means.

It will be noted that the inner walls 356, 357, and 358, in cooperation with the outer walls 342, 344, and 341 form a plurality of channels through which the side wall members 324 and the deflector plate 325 slide. The inner walls 356, 357, and 358 insure that any clinkers entering the receptacle will not assume a position in the path of movement of the side walls 324 or the deflector plate 325. In other words, the inner and outer walls in cooperation serve to provide channels for the side walls 324 and deflector plate 325 which are always clear of clinkers.

In use, the lid assembly 321 is withdrawn from the receptacle 340 sufficiently to permit the cover 322 to be secured to the top of the fire door opening as with the species of Figures 1 to 5. In order to simplify the illustration, the means for securing the cover 322 to the top of the firedoor opening is not shown. It is to be understood, however, that a means similar to catch 28 is provided for this purpose. The operator may view the fire through the glass pane of the lid assembly as he withdraws the clinkers. As with the species of Figures 1 to 5, the clinkers are dropped downwardly without being brought into the furnace room. In the present case, they pass downwardly within the walls 356, 357, 345, and 358, remaining at all times out of the path of

movement of the lid assembly. As soon as all of the clinkers have been removed, the lid assembly is dropped down to the position shown in Figure 9 in which all escape of fumes from the receptacle is prevented.

While the arrangement of Figures 9 and 10 is more limited as to the capacity of the receptacle and has certain other minor disadvantages, it offers the advantage of greater economy. Furthermore, it retains certain of the basic features of the previously described species in that it is normally out of the path of the firing door and provides means which, when this lid assembly is raised, constitutes an enclosure for removing the clinkers without any possibility of fumes or ashes escaping into the furnace room.

Conclusion

In general, while I have shown certain specific embodiments of my invention, it is to be understood that this is for purposes of illustration only and that my invention is to be limited only by the scope of the appended claims.

I claim:

1. In combination with a furnace having a firing opening normally covered by a firing door, a chamber adapted to receive clinkers and ashes, and a clinker receiving and guiding member supported for sliding movement in a substantially vertical direction and adapted to be slidably raised and lowered with respect to said chamber between an uppermost position in which it surrounds said firing opening and a lowermost position in which it is out of the path of said firing door while remaining slidably associated with said chamber.

2. In combination with a furnace having a firing opening normally covered by a firing door, a chamber adapted to receive clinkers and ashes, and a clinker receiving and guiding member supported for sliding movement in a substantially vertical direction and adapted to be raised and lowered with respect to said chamber between an uppermost position in which it surrounds said firing opening and a lowermost position in which it is out of the path of said firing door and closes the upper end of said chamber.

3. In a furnace attachment designed to be positioned adjacent a furnace to facilitate the removal of clinkers therefrom, a receptacle, a chute communicating with said receptacle, and a lid assembly comprising a cover of an area to cover the upper end of said chute and a pair of side walls extending downwardly and telescoping with said chute, said side walls being of a length sufficient to support said lid assembly with respect to said chute after the cover member has been raised above the top of the firing opening of the furnace.

4. In a furnace attachment designed to be positioned adjacent a furnace to facilitate the removal of clinkers therefrom; a receptacle; a chute communicating with said receptacle; and a lid assembly comprising a lid of an area to cover the upper end of said chute, a pair of side walls extending downwardly and telescoping with said chute, and an inverted U-shaped sleeve slidably secured to said side walls, said side walls being of a length sufficient to support said lid assembly with respect to said chute after the cover member has been raised above the top of the firing opening of the furnace, and said sleeve being effective when moved to the rear to close any gap between said lid assembly and said furnace.

5. In a furnace attachment designed to be po-

sitioned adjacent a furnace to facilitate the removal of clinkers therefrom; a receptacle; a chute having its open lower end directed toward said receptacle; a sleeve slidably secured within said chute and adapted in its lowermost position to connect said chute to said receptacle; and a lid assembly comprising a lid of an area to cover the upper end of said chute and a pair of side walls extending downwardly and telescoping with said chute, said side walls being of a length sufficient to support said lid assembly with respect to said chute after the cover member has been raised above the top of the firing opening of the furnace.

6. In a furnace attachment designed to be positioned adjacent a furnace to facilitate the removal of clinkers therefrom; a receptacle; a chute adapted to be supported on the floor of the furnace room; means for detachably connecting said chute to said receptacle; and a lid assembly connected to said chute in a telescoping manner; said lid assembly comprising a cover adapted to fit over and cover the upper end of said chute when said cover is in its lowermost position, a pair of side walls having a telescoping fit with said chute, and a deflector plate extending between said side walls in the front of said lid assembly and spaced from said cover sufficiently to permit the insertion of clinker removing tools therebetween.

7. In a furnace attachment designed to be positioned adjacent a furnace to facilitate the removal of clinkers therefrom; a receptacle; a chute adapted to be supported on the floor of the furnace room; means for detachably connecting said chute to said receptacle; and a lid assembly connected to said chute in a telescoping manner; said lid assembly comprising a cover adapted to fit over and cover the upper end of said chute, when said cover is in its lowermost position, a pair of side walls having a telescoping fit with said chute, a pane of transparent material extending between said side walls a substantial distance below said cover member, and a deflector plate extending between said side walls in the front of said lid assembly and spaced from said pane of transparent material sufficiently to permit the insertion of clinker removing tools therebetween.

8. In combination with a furnace having a firing opening normally covered by a firing door, a receptacle adapted to receive clinkers and ashes and having double side walls, and a clinker receiving and guiding member comprising a cover member and side walls disposed in a telescoping manner within said side walls, said guiding member being adapted to be raised and lowered with respect to said chamber between an uppermost position in which it surrounds said firing opening and a lowermost position in which it is out of the path of said firing door.

9. In combination with a furnace having a firing opening normally covered by a firing door, a receptacle adapted to receive clinkers and ashes and having double side walls and a double front wall, and a clinker receiving and guiding member comprising a cover member, side walls, and a deflector plate extending between said side walls in front of said member, said side walls and deflector plate being disposed in a telescoping manner in said double side walls and double front wall, said guiding member being adapted to be raised and lowered with respect to said chamber between an uppermost position in which it surrounds said firing opening and a lowermost po-

sition in which it is out of the path of said firing door.

10. In combination with a furnace having a firing opening normally covered by a firing door, a chamber adapted to receive clinkers and ashes, and a clinker receiving and guiding member of substantially the same horizontal depth as said

chamber and supported for sliding movement between an uppermost position in which it surrounds said firing opening and a lowermost position in which it is out of the path of said firing door and forms an ash-tight closure for said chamber.

EDWARD J. ANDERSON.
